MANY

MEANS FOR SETTING TYPE LEVERS

Application filed December 27, 1928, Serial No. 328,708, and in Germany December 23, 1927.

This invention relates to a device for bending a typewriter type lever by the proper amount, for measuring this bending, and for detecting any improper twisting of the type lever.

The device according to the present invention includes as its chief features the following:

1. A clamping device which holds the lever tightly in fixed position up to the point where bending is to take place.

2. A bending and direction member connected to a clamp which engages the head of the type lever (the portion to be bent) up to the point where bending is to take place.

3. A scale on which variations from the correct angular bending of the head and any twisting of the head may be detected in magnified proportions, this scale comprising:

20 (a) indicating means on the free end of the bending lever.

(b) scale members rigidly connected to the clamping means.

In the illustrated form of the invention, 25 there is a circular scale fixed to the clamping means and a pointer mounted on a cross member secured to the direction member at a right angle thereto, the cross member lying in the plane of movement of the direction member.

30 The pointer shows by its displacement on the scale the angular displacement of the direction member, and the cross member indicates by its angular displacement from the plane of the scale any twist which may have been 35 imparted to the type lever.

In the drawings, which show one form of the invention:

Fig. 1 is a cross section of the device on the line 1—1 of Fig. 2.

40 Fig. 2 is a top plan view of the device.

In the form shown, a base plate *d* is provided with two lugs *a*, *a*, a raised portion *z*, and a scale *b*. In one of the lugs *a* the tensioning member *v* is slidably but non-rotatably mounted. The member *v* can be moved 45 by the screw *u* which is turned by handle *t*.

A cylindrical member *w* fits tightly in the other lug *a*. A pin *x* is secured in one end 50 of member *w* and extends into a longitudinal bore in member *v*. On the second lug are

mounted a pin *l* and an eccentric disc *m* mounted on a shaft *n* and operated by a handle *o*.

On the raised portion *z* are mounted two blocks *q* slidable in undercut grooves *p*. The blocks are provided with upward extensions *r* substantially triangular in cross section. The straight vertical edges *c* of the upward extension *r* form bending edges upon which the type lever is bent.

Before clamping the type lever *f* into position, the members *v* and *w* are separated by withdrawal of the screw *u*. By turning the handle *o* the eccentric *m* is turned to the point where its edge is at the greatest possible distance from the pin *l*, and this distance is greater than the width of the type lever.

The rear end of the type lever is now placed between members *v* and *w* in such a way that the hook rests on the pin *x* as shown in Fig. 1. The body of the lever now lies between pin *l* and eccentric *m* and between the two upward extensions *r*. The members *v* and *w* are now moved towards each other, but are not tightly clamped, so that lever *f* may still pivot around pin *x*. Handle *o* is then operated to turn eccentric *m* so that it will clamp the lever tightly against the pin *l*. Members *v* and *w* are now clamped tightly together to hold the type lever firmly in place.

The members *v* and *w*, the pin *l* and eccentric *m*, and the extensions *r* on blocks *q*, all mounted on the base *d*, serve to hold the lever against movement, and as these holding means extend up to the portion to be bent, the lever must always bend at the proper point.

The bending lever or extension member *e* is now clamped tightly to the portion of lever *f* which is to be bent. This is accomplished by a clamp member *g*, a nut and bolt *y*, and an eccentric lever *g*, operating on clamp member *g* to press it against one end *g* of extension member *e* to clamp the head of the type lever tightly therebetween. The end of the extension member is provided with a suitably shaped recess in which the head of the type lever fits.

The type levers are placed in the clamps and the extension member may be turned by

any desirable amount to give the proper angle to the lever *f*.

Means are supplied for indicating the bending of the lever and for detecting any twist in the lever such as sometimes occurs during bending. On the base plate *d* is a horizontal semicircular scale *b* with scale divisions marked thereon. On the extension member *e* is a cross member *i* substantially perpendicular to the member *e* and closely adjoining the scale *b* and curved similarly to the scale *b*. This, as shown in Fig. 1, is normally in the plane of the scale *b*. On this cross member is a pointer *k* to indicate the various scale divisions. The scale divisions are preferably so arranged that the pointer *k* points to scale division *o* when the extension member is clamped to a straight type lever. On the end of the extension member is a handle *h* for manipulation of the extension member.

In the present form there are twenty-two scale divisions on each side of the zero point, so that forty-five different bendings of the head of the type lever are permitted. If the point 10 is chosen for the final bending angle of any lever, the lever is bent until pointer *k* is slightly beyond 10, say at 12, and the lever is then released. The spring of the lever then carries the pointer back to 10, or possibly farther. This bending is repeated until the pointer remains on the scale division 10. The fact that the levers are generally formed of spring steel makes this operation necessary.

If any twisting of the type lever occurs during bending, the cross member *i* will be bent from the plane of the scale *b*. This will easily be detected and corrected by twisting the handle *h* until the twist is removed. The advantage of the device is that errors in the bending and the presence of twist are both shown on an enlarged scale. Also, the bending lever is perfectly free to move, and the type lever will have the same shape to which it has been set after it is removed from the device. In addition, the correctness of the set may be judged at once without removing the type lever from the device, and any errors may be corrected.

While I have described herein one embodiment of my invention, I wish it to be understood that I do not intend to limit myself thereby except within the scope of the appended claims.

I claim:

1. A device for bending type levers comprising means extending up to the portion to be bent for holding said lever against movement, an extension member adapted to be secured to the portion to be bent, and cooperating means on said extension and on said holding means for indicating the bending and twisting of said lever.

65 2. A device as claimed in claim 1, said in-

dicating means including a scale secured to said holding means and a pointer on said extension adapted to cooperate with said scale.

3. A device as claimed in claim 1, said indicating means comprising a horizontal scale secured to said holding means and a substantially horizontal plate secured to said extension and having a pointer thereon, said plate cooperating with said scale to indicate twisting of the lever and said pointer cooperating with said scale to indicate bending of the lever.

In testimony whereof I have affixed my signature.

HANS LUCE.
